INVERSE FEED-BACK AMPLIFIER

Donald Gordon Lindsay, Kogarah, near Sydney, New South Wales, Australia, assignor to Amalgamated Wireless (Australasia) Limited, Sydney, New South Wales, Australia, a company of New South Wales, Australia

Application November 15, 1939, Serial No. 304,562
In Australia November 15, 1938

6 Claims. (Cl. 179—171)

This invention relates to inverse feed-back amplifiers and has particular reference to amplifier circuit arrangements in which inverse feedback is employed to counteract distortion.

With amplifier equipment, particularly for broadcasting purposes, it is often desired to operate separate amplifier output channels from a common input source. Such an arrangement is commonly used when "splitting" a programme between several lines, separates output valves being used for each line to obviate a complete break in the programme should one line "short" or become noisy.

In addition, and for similar reasons, separate channels are often desirable in programme amplifiers, for feeding the monitoring system and the main programme circuit. To compensate for non-linear distortions in the amplifying characteristics, it is highly desirable that such arrangements be available for use with inverse feedback circuits; but the usual circuits of this type introduce two serious difficulties. If the feedback is derived from a portion of the plate circuit of each of, say, three stages, and fed back to the input of the same stage, or further back if desired, an E. M. F. impressed on the output terminals of one stage appears in both the others not greatly reduced in magnitude. This means of course that noise on one output line can appear at the output of the other channels, and in general the channels are effectively coupled together by the inclusion of such feedback. In addition, variation of load on one output, from open circuit conditions to the limiting case of a short circuit, alters the total amount of feedback, and consequently the overall gain, by appreciable amounts.

Both of the foregoing effects vary with the amount of feedback and the method of applying it and it is difficult to obtain a worthwhile amount of inverse feedback by known methods without introducing the aforesaid effects.

The principal object of the present invention is, therefore, to provide an improved method of deriving feedback potentials for use in inverse feedback circuit arrangements, which permits a large amount of feedback to be obtained in a simple manner with excellent stability, and which is not subject to the foregoing undesirable characteristics.

A further object of the invention is to provide a method of deriving feedback potentials which has certain advantageous features in normal inverse feedback applications, in that undesirable phase shift is reduced.

A still further object of the invention is to provide an improved method of obtaining feed-back potentials for use in connection with inverse feedback circuit arrangements employed in multiple output amplifiers.

In accordance with this invention feedback potentials for a circuit arrangement employing inverse feedback are derived from across a load impedance in the screen grid circuit of a multiple grid output valve or valves.

The invention is now described and illustrated in connection with the accompanying drawing.

In the said drawing

Figure 1 is a circuit diagram showing one method of deriving feedback potentials in accordance with this invention, and

Figure 2 shows a method of applying the invention to an amplifier having multiple output stages.

Referring to Figure 1, the output stage of an amplifier is shown as employing a pentode valve 5 having a cathode 19, a control grid 20, a screen grid 21, a suppressor grid 22 and an anode 23.

Alternating potentials which are to be amplified are fed to the input terminals 17, 18, and applied to the grid 20 through the medium of coupling condenser 15 and across the grid resistor 16. The grid 20 is given its desired potential bias by means of a so-called self-biasing resistor 3 connected between cathode 19 and ground. Those skilled in the art are well acquainted with this method of obtaining a suitable grid biasing potential and hence it will be readily understood that the bias is obtained due to the voltage drop across resistor 3 when current flows through the anode-cathode circuit. The voltage thus developed across the resistor 3 is applied to the grid 20 through the grid resistor 16. A by-pass condenser 4 is connected in shunt across resistor 3 in order to provide a low impedance path to ground for alternating currents of relatively high frequency flowing in the cathode circuit. Although the "self-biasing" method has been described for obtaining biasing potentials for the grid, it is to be clearly understood that any well known method of applying the desired biasing potentials to grid 20 may be employed without affecting the scope of this invention.

Operating potentials are applied to the anode 23 from the positive terminal 25 of a potential supply source (not shown) through the primary winding of the output transformer 6, the secondary of which is connected to the utilisation means.

The required voltage is applied to the screen grid 21 from the aforesaid positive terminal 25 through the filter network 8, 9, and the series connected impedance 7. The decoupling impedance 8 may be an inductance, or a resistance as shown.

Feedback potentials are obtained in accordance with this invention from a potential divider comprising condenser 11 and resistors 10, 14, con-

nected in series across the load impedance 7, 8, 9, in the screen circuit.

The values of components 15, 16, 3, 4 and 6 can be normal for components usually associated with this type of circuit. Components 7, 8, 9, 10, 11 and 14 are associated with the feedback circuit and their relative values are controlled by the considerations hereinafter explained.

The decoupling impedance 8 provides isolation of the A. C. potentials on the screen from the normal high voltage supply circuit, and where frequency compensated feedback is required an impedance value is selected for 8 which enables the condenser 9 to be of such a value that the feedback network is compensated suitably at low frequencies, as it will be apparent that the impedance of 9 is actually a portion of the load impedance in the screen circuit.

In an experimental assembly where 5 was a type 6F6G pentode valve and 15, 16, 3, 4 and 6 of usual values, the decoupling resistor 8 was 10,000 ohms. However, although 10,000 ohms was the actual value adopted, the value is not critical, and any value between 5,000 and 20,000 ohms may be employed without seriously affecting the operation of the invention.

In order to keep phase shift at a minimum and also to maintain the usual operating potentials and conditions in a simple manner, resistor 7 should be of a low value. Where feedback is arranged over an amplifier of reasonably high gain, the value of the component 7 may be between 100 and 2,000 ohms. In an experimental application a value of 1,000 ohms was used for 7 and 12 microfarads for 9. Between certain limits dependent on other components, increase in the capacity value of 9 decreases the feedback at low frequencies compared with that at higher frequencies.

Condenser 11 is necessary in the example shown in Figure 1 to block the high voltage potential from other portions of the feedback network and is also effective in compensating the feedback at low frequencies. Decrease in the value of condenser 11 decreases the feedback at low frequencies, and therefore relative values of the components 9 and 11 can be adjusted to obtain adequate low frequency compensation. The actual value of 11 depends on the values chosen for 10 and 12, and the other components of the feedback network. In experimental tests values of between 0.1 and 2 microfarads were used for 11, suitable compensation being obtained in final tests with a value of 0.5 microfarad.

Components 10, 12, 14, depend on the value chosen for 7, the characteristics of the subsequent circuit to which the feedback is to be connected, and the amount of feedback desired. Various values of all these components were used in the experimental set-up; and the final values chosen when applying feedback to an input transformer of a previous stage, as in Figure 2, were as follows:

	Ohms
Resistor 10	15,000
Resistor 12	1,000
Resistor 14	2,000

The condenser 13 connected in shunt across the resistor 12 provides high frequency compensation in the feedback path.

Whilst an improved method has been described of deriving feedback potentials by the use of a potential divider across the load impedance in the screen circuit of a pentode valve, it will be

realised that the feedback network itself can take any of the usual forms known in the art, and that the circuit and values of Figure 1 are explained for the purposes of illustration only and represent practical arrangements used with the particular application for which the whole circuit arrangement was developed.

In the application of the invention to an amplifier feeding a plurality of output channels, as exemplified by Figure 2, the method disclosed by Figure 1 is slightly modified.

In this modified arrangement a single stage amplifying valve 38 is shown with its grid coupled to the input terminals 41 through the transformer 40, and its anode coupled to the grids of the parallel connected output valves 5, 5a through the resistance capacity coupling network 32, 15, 16. The anodes of the parallel output valves 5, 5a are coupled to separate utilization means 20 through the output coupling transformers 6 and 6a respectively.

Operating potentials are supplied to the anodes of the valves 5, 5a from the positive terminal H. T. of the supply source (not shown) through the impedances 28, 29, and to the anode of valve 38 through the decoupling network 31, 33 and the anode resistor 32. Potentials for the screen grid of valve 38 are taken from a common connection between resistors 31, 32 through a dropping resistor 34. The by-pass condenser 35 maintains the screen at cathode potential for the alternating potentials which are to be amplified. Biasing potentials are supplied to the grids of the separate valves through self-biasing networks 36 in the individual cathode leads.

The feedback arrangement and its operation are substantially the same as described in connection with Fig. 1 and, as like reference numerals have been used to indicate like parts, a further description is considered unnecessary.

The feedback load, 7, 8 and 9 is shown in Fig. 2 common to both screens as it was found that no undesirable effects were thus created.

Feedback potentials are taken from the potential divider 11, 10, 14, in the present example and fed to the input of the valve 38 in degenerative sense, through a tertiary winding on the transformer 40 and the frequency compensating network 12, 13.

The feedback could, of course, be connected through other types of networks to different points in the amplifier by methods well known in the art, and the above is merely one example of its application to a particular experimental arrangement.

Whilst both in Fig. 1 and in Fig. 2 the feedback network has been shown as frequency compensated, it is to be understood that it is within the scope of this invention to dispense with the compensation if desired.

I claim:

1. An amplifier circuit arrangement comprising a plurality of electron discharge tube stages, each tube of which includes a cathode, an anode, a control grid and a screen grid, said screen grids of stages following a first stage being connected in parallel, means for producing inverse feedback potentials on the control grid of the tube in the first stage, said means including a load impedance in circuit with said parallel connected screen grids, and means for rendering said load impedance frequency-dependent.

2. A circuit arrangement according to claim 1 in which said load impedance is constituted by series-connected resistance elements, and the

last said means is constituted by resistive and capacitive elements of a filter system.

3. A circuit arrangement comprising a plurality of multi-grid electron discharge tubes, one of said tubes being in a first stage and the remaining tube complement being in a second stage, parallel connections to corresponding grids of the second stage tubes, and inverse feed-back means adapted to apply control-energy to the tube of the first stage, said control energy being derived from potential variations on those parallel-connected grids of the second stage which serve as screen grids.

4. A device according to claim 3 and having a frequency-dependent filter included in said feed-back means.

5. An amplifier circuit arrangement comprising a pentode discharge tube in a first stage, a plurality of parallel connected pentode discharge tubes in a second stage, said second stage tubes having independent output circuits and having screen grids which are parallel-connected to a

common load impedance, and means for deriving from said load impedance inverse feed-back potentials for partial control of the tube in the first stage.

6. An amplifier circuit arrangement comprising two stages of discharge tubes the second stage comprising a plurality of tubes having parallel-connected input circuits and a plurality of independent output circuits, each tube having a cathode, an anode, and at least two grids including a control grid and a screen grid, an inverse feed-back circuit connected between the screen grids of the second stage and the control grid of the first stage, frequency dependent elements in said feed-back circuit, a source of operating potential, and a load impedance interposed between said source and the screen grids of the second stage, said load impedance being effective to produce the wanted feed-back potentials in said feed-back circuit.
